WILLIAM A. TROUT, OF LOS ANGELES, CALIFORNIA.

OIL-WELL DERRICK AND METHOD OF SHORTENING SAME.

Application filed November 5, 1925. Serial No. 67,190.

My invention relates to the oil producing industry, and it relates particularly to a steel derrick which is useful in this industry.

In this industry a derrick is installed previous to the drilling of a well for the purpose of handling the various equipment during the drilling of the well, and also during the pumping period thereof. While drilling the well the derrick is called upon to handle enormous loads and must endure great strains, besides supporting certain machinery such as the draw-works. After the well has been drilled and the casing set, the derrick is no longer required to handle great loads or withstand severe strains, but is used for handling the pump tubing and sucker rods which are comparatively light when contrasted with the drill pipe and other drilling equipment. It is general practice to remove all the equipment of the derrick after the well has been drilled except that necessary to operate the pump, and that used to remove the pump tubing and rods from the well.

Since the derrick is not required to handle great loads or endure rigorous strains during pumping, it is plainly evident that only a light derrick is necessary at this time. A heavy derrick, such as used during drilling, is quite an expensive investment and as a matter of economy some companies have established a practice of dismantling the heavy derrick, used during drilling, and of replacing it by a lighter derrick when the drilling is completed, the heavy derrick being assembled elsewhere for use in drilling another well. Although this practice is cheaper than providing a new derrick for each well, the labor of dismantling and assembling is quite an expensive item.

It is an object of this invention to provide a method for suspending the upper part and removing an intermediate part of a drilling derrick, then lowering the upper part of the derrick into position for handling the pumping equipment and subsequently removing the lower part of the drilling derrick. The upper part of a heavy derrick, less certain reinforcing elements hereinafter referred to, is practically the same in construction as the lighter derricks used to replace these heavy derricks. Only by thus lowering the upper part and removing the lower part of the heavy derrick are dismantling and subsequent assembling of the upper part of the derrick eliminated, and

an appreciable saving is brought to pass. The lower part of the derrick is, of course, used at another well during drilling.

It is another object of my invention to provide a method for converting a drilling derrick, or heavy derrick, into a pumping derrick, or light derrick, which consists in attaching gins or lowering mechanism to a derrick, and disconnecting the upper and lower parts of the derrick from an intermediate part and removing said intermediate part so that the upper part may be lowered within the lower part by the lowering mechanism, into a position to be used for pumping.

Other objects and the particular advantages of my invention will be made evident hereinafter.

Referring to the drawings in which I illustrate my invention:

Fig. 1 is an elevational view of a derrick of my invention showing the gins or lowering mechanism in place.

Fig. 2 is a view of the derrick showing an intermediate part thereof removed and the upper part of the derrick ready for lowering.

Fig. 3 is an elevational view of the derrick showing the upper part thereof lowered into engagement with a base.

Fig. 4 is a view of the upper part of the derrick, per se, the lowering mechanism and the lower part thereof being dismantled and removed from place.

Fig. 5 is a section taken substantially as indicated by the line 5—5 of Fig. 1, showing bracing of the lowering mechanism.

Fig. 6 is an enlarged fragmentary detail taken on the line 6—6 of Fig. 2, showing the upper end of one of the gin posts of the lowering mechanism and the manner in which the upper part of the derrick is supported.

Fig. 7 is an enlarged fragmentary elevational view showing the upper end of one of the gin posts of the lowering mechanism and the manner in which the upper part of the derrick is supported.

Fig. 8 is a fragmentary section taken substantially as indicated by the line 8—8 of Fig. 2, showing the manner in which the gin posts of the lowering mechanism are secured to the lower part of the derrick.

Fig. 9 is an enlarged fragmentary view showing the winch construction of my invention, this view being taken substantially as indicated by the line 9—9 of Fig. 2.

With reference to Figs. 1 to 4 of the drawings, the derrick of my invention consists of substantially vertically extending legs 11 which are positioned at the corners 5 of the derrick. These legs are braced and attached together by suitable cross bracing 12. In the derrick, as originally erected, the legs 11 may be reinforced by members (not shown) which may be removed at the 10 conclusion of the drilling operation. As clearly shown, the legs 11 converge as they approach the upper end of the derrick, the derrick being in the form of a truncated pyramid. I provide the standard form of 15 water table 12^a and platform 13.

The derrick of my invention is divided into three sections which are indicated in Fig. 1. The derrick consists of a lower section indicated at A, an intermediate section 20 indicated at B and an upper section indicated at C. The lower section A is constructed so that it accommodates the customary derrick equipment. In the drawings the derrick is shown looking from the 25 walking beam side thereof. The lower part A is therefore constructed so as to provide a vertically extending elongated opening 17 through which a walking beam may project. The upper section C is provided with an 30 identical vertically extending elongated opening 18. This opening 18 is in substantially the same position and is the same distance from the lower end of the upper part C as is the opening 17 from the lower end 35 of the lower part A. It is to be understood that on the other sides of the derrick the constructions of the lower and upper parts may be identical in the same respects as the walking beam side of the derrick. The purpose 40 of such arrangement will be described hereinafter.

When it is desired to convert the derrick shown in the drawings from a drilling derrick into a pumping derrick, the removable 45 members, if such are used, which reinforce the corner members are removed and the lowering mechanism of my invention is secured in place.

The lowering mechanism consists of substantially 50 vertically extending gin posts 20 which are secured to the legs 11^a of the lower part A of the derrick. As shown in Fig. 8, the posts 20 may be formed from angle irons and are secured to the legs 11^a 55 by angle brackets 21 which are positioned as shown clearly in Fig. 8. The angle brackets 21 are permanently secured to the posts 20 by rivets 23, whereas they are removably secured to the legs 11^a by bolts 24. The angle 60 brackets 21 are rigidly secured to the posts 20 since there is no need for separation, whereas they are removably secured to the legs 11^a so that they may be secured to different derricks when these derricks are to 65 be converted from a drilling derrick into a

pumping derrick. The upper ends of the posts 20, as shown in Fig. 7, are provided with sheaves 26 which are supported from the posts 20 by means of suitable brackets 27. As shown in Fig. 5, the sheaves 26 are 70 in planes which cross at the center of the derrick. The posts 20 are braced at their upper ends by horizontal braces 28 which are secured to the posts by bolts 29.

Near the lower ends of the legs 11^a are 75 winches 30. As clearly shown in Fig. 9, the winches 30 each consists of frame members 32 and 33 which provide flanges 34 adapted to contact the outer faces of the legs 11^a. These flanges 34 are removably secured to 80 the legs 11^a by bolts 36. The frame 32 is L-shaped having a portion 37, and the plane 33 is Z-shaped having a portion 38 which extends substantially parallel to the portion 37, but is spaced a distance therefrom. Extending between these portions 37 and 38 is a shaft 39 which carries a drum 40. Secured to the shaft 39 or the drum 40 is a gear 41 which is meshed with a pinion 42 by which it is rotated in a manner to revolve the drum 40. This pinion 42 is carried on a shaft 44 which extends between the portions 37 and 38, which shaft has a polygonal portion 45 formed on one end 90 thereof in order to accommodate a suitable wrench or crank for revolving the shaft in order to operate the winch 30. A collar 47 is secured to the shaft having holes 48 adapted to receive a pin 50. The pin 50 when extended into one of the holes 48 engages the frame 33 and prevents a rotation of the shaft 44 and likewise a rotation of the drum 40. The winch shown is of conventional design and any other well known form of lifting device may be substituted therefor. Carried on the spool portion of the drum 40 of each of the winches 30 is a cable 55. The cables 55 extend upwardly, as shown in the drawings, and extend over the sheaves 26 and are secured, as shown in Fig. 6, to the lower corners of the upper part C of the derrick. These cables have loops 56 formed at the upper end thereof which extend through openings 57 formed at the lower corners of the part C of the derrick.

After the lowering mechanism has been placed, the winches 30 are operated to place a tension on the cables 55. When this tension is great enough, the weight of the upper part C of the derrick is transferred to the lower part of the derrick, not through the intermediate part B but through the lowering mechanism. The part B of the derrick is then removed from place, this part being so constructed that it can be easily dismantled when the weight thereon is removed. During this time the upper part C of the derrick is stabilized and prevented from toppling by suitable guy cables 59 which extend from the upper end of the part C to 120

the ground. In Fig. 2 I show the derrick of my invention with the upper part C thereof supported entirely by the lowering mechanism of my invention, the intermediate section B having been removed from place.

The next operation is to lower the upper part C of the derrick so that it rests on the base or foundation for the derrick. The upper part C is shown in lowered position in Fig. 3. This is accomplished by operating the winches 30 to unwind the cables 55. After the upper part C has been lowered, as shown in Fig. 3, the lowering mechanism may be detached therefrom and removed from place, and the lower part A of the derrick may be dismantled. In Fig. 4 the upper part of the derrick is shown by itself, the lowering mechanism and the lower part A of the derrick being dismantled. The lower part A of the derrick may be assembled and used as the lower part of another derrick at some other well.

As shown in Fig. 4, the opening 18, when the upper part C is moved into lowered position, occupies the same vertical position which the opening 17, of the lower part A of the derrick, occupied when it was in place. During pumping, the walking beam which may have previously projected through the opening 17 will now project through the opening 18. This is an important feature of my invention, since it eliminates the necessity for any reconstruction. From Fig. 1 it will be seen that the lower part of the derrick A and the lower portion of the upper part C are substantially the same in construction, this being quite important as previously pointed out. Certain of the cross bracings of the lower end of the upper part C of the derrick may be removed as shown in Fig. 4 and vertical members indicated by dotted lines 60 may be provided for supporting a calf wheel or other equipment of the derrick. It is quite obvious that the removing and replacing of these parts may be easily accomplished.

My invention has produced great economies in the oil producing industry, since my type of derrick can be easily converted from a drilling into a pumping derrick. The necessity of leaving an expensive heavy derrick at a well when only a light derrick is necessary or the complete dismantling of a heavy derrick and the replacing of it by a lighter derrick is eliminated by my invention. As clearly stated and illustrated heretofore, the upper part C of my derrick is substantially the same construction as the lighter derricks by which the heavy derricks are frequently replaced. The lower part A of my derrick is of substantially standard construction and may be removed from place by the method and apparatus of my invention, leaving only the upper and lighter part of the derrick.

I claim as my invention:

1. A method of converting a drilling derrick into a pumping derrick comprising: removing an intermediate part of a derrick, said intermediate part being situated between upper and lower parts thereof; and lowering said upper part into pumping position. 70

2. A method of converting a drilling derrick into a pumping derrick comprising: supporting the weight of an upper part of a derrick; removing an intermediate part of a derrick, said intermediate part being situated between upper and lower parts thereof; and lowering said upper part into pumping 80 position. 75

3. In combination: a derrick comprising an upper part, an intermediate part and a lower part; and mechanism arranged to receive the weight of said upper part so that 85 said intermediate part may be disconnected and removed from said upper and lower parts, said mechanism being so positioned and attached to said upper part that, upon the removal of said intermediate part, said 90 upper part may be lowered directly to a position of rest upon the base of said lower part.

4. In combination: a derrick comprising an upper part, an intermediate part and a 95 lower part; and mechanism carried by said lower part and arranged to receive the weight of said upper part so that said intermediate part may be disconnected and removed from said upper and lower parts, said mechanism 100 being so positioned and attached to said upper part that, upon the removal of said intermediate part, said upper part may be lowered directly to a position of rest upon the base of said lower part. 105

5. In combination: a derrick comprising an upper part, and intermediate part and a lower part; gin poles secured to said lower part; sheaves mounted at the upper ends of said gin poles; cables extending over said 110 sheaves and being attached to said upper part; and winches secured to said lower part on which winches said cables are wound, said winches being operable to wind said cables thereon to support said upper part so 115 that said intermediate part may be disconnected and removed, and to unwind said cables to subsequently lower said upper part into lowered position.

6. In combination: a derrick; a lower construction at the lower end of said derrick adapted to accommodate certain equipment of said derrick; and an upper construction above said lower construction similar to said lower construction, said upper construction being adapted to accommodate the same equipment accommodated by said lower construction when the upper part of said derrick is separately used as a pumping derrick. 125

7. In combination: a derrick comprising 130

- 4
- an upper part, an intermediate part and a lower part; mechanism arranged to support the weight of said upper part so that said intermediate part may be disconnected from 5 said lower and upper parts and removed, said mechanism being operable to subsequently lower said upper part; a lower construction in said lower part, adapted to accommodate certain derrick equipment; and 10 an upper construction in said upper part, said upper construction being arranged to accommodate the same equipment accommodated by said lower construction when said upper part is lowered into pumping position. 15
8. A method of converting a drilling derrick into a pumping derrick which comprises: supporting an upper portion of said drilling derrick of sufficient size to act as a 20 pumping derrick so that parts of the drilling
- derrick can be removed from below said upper portion; and thereafter lowering said upper portion into pumping position through the space left by said removal. 25
9. A method of converting a drilling derrick into a pumping derrick which comprises: providing a drilling derrick, the upper portion of which is suitable for use as a pumping derrick; supporting the weight of said upper portion independently of the remainder of the derrick; removing a sufficient amount of said remainder to allow said upper portion to be freely lowered into pumping position; and thereafter so lowering said upper portion. 30
- In testimony whereof, I have hereunto set my hand at Los Angeles, California, this 26th day of October, 1925. 35

WILLIAM A. TROUT.
